UNITED STATES PATENT OFFICE.

RICHARD J. McDONOUGH, OF CLEVELAND, OHIO.

DESIGN FOR A SIGNAL-LAMP CASING.

60,420.

Specification for Design.

Patented Feb. 14, 1922.

Application filed June 21, 1921. Serial No. 479,374. Term of patent 7 years.

To all whom it may concern:

Be it known that I, RICHARD J. McDONOUGH, a citizen of the United States, residing at Cleveland, in the county of Cuyahoga and State of Ohio, have invented a new, original, and ornamental Design for Signal-Lamp Casings, of which the following is a specification, reference being had to the accompanying drawing, forming a part thereof.

Figure 1 of said drawing is a front view of the signal lamp casing,

Fig. 2 is a top view thereof,

Fig. 3 is a rear view, and

Fig. 4 is an end view of the signal lamp casing with a supporting bracket therefor indicated by dotted lines.

I claim:

The ornamental design for a signal lamp casing, as shown.

In testimony whereof I do now affix my signature.

RICHARD J. McDONOUGH.
